NO. 14,945

April 8, 1884

UNITED STATES PATENT OFFICE.

WILLIAM M. GARTSHORE, OF LONDON, ONTARIO, CANADA.

DESIGN FOR A COOKING-STOVE.

SPECIFICATION forming part of Design No. 14,945, dated April 8, 1884.

Application filed March 3, 1884. Term of patent 7 years.

To all whom it may concern:

Be it known that I, WILLIAM M. GARTSHORE, of London, in the county of Middlesex and Province of Ontario, Canada, have invented a new and original Design for Cooking-Stoves, of which the following is a specification.

The drawing is a perspective.

Heretofore cooking stoves and ranges have been made rectangular; and the new design which I have invented and produced consists in a cooking-stove with the ordinary flat top and square sides and ends, except that the part of the front which surrounds and contains the fire-pot is polygonal, and has mica windows on one or more of its sides to show the fire, in imitation of a base-burner.

In my new design, A is the flat top; B, the square lower portion of the front, and C the polygonal upper portion of the front, sur-

rounding the fire-pot, having therein one or 20 more mica windows, G. D E represent doors of the oven and plate-warming compartment, and F represents a water-heater of the usual form employed when no water-back is used.

What I claim as my design, and desire to secure by Letters Patent, is—

1. The herein-described design for a cooking-stove having a flat top, rectangular sides, and a polygonal front surrounding the fire-pot.

2. The herein-described design for a cooking-stove having a flat top, rectangular sides, and a polygonal front surrounding the fire-pot, and having mica windows in the sides thereof.

WILLIAM M. GARTSHORE.
